INVENTOR:

Frederick G. Warrell,
By his Attorney
Horace Petit.

UNITED STATES PATENT OFFICE.

FREDERICK G. WARRELL, OF PHILADELPHIA, PENNSYLVANIA.

FUSE-BLOCK.

SPECIFICATION forming part of Letters Patent No. 426,156, dated April 22, 1890.

Application filed February 3, 1890. Serial No. 339,049. (No model.)

To all whom it may concern:

Be it known that I, FREDERICK G. WARRELL, of the city of Philadelphia, State of Pennsylvania, have invented a certain new and useful Improvement in Electric Cut-Outs; and I do hereby declare the following to be a full, clear, and exact description thereof, reference being had to the accompanying drawings, forming a part of this specification.

10 My invention has relation to electric cut-outs; and it consists in a removable porcelain shell or casing surmounting and surrounding an inclosed base or core of like material, upon which is secured by any suitable means the two ends of the electric wires, set apart from each other, but connected by a fusible wire adapted to fuse at a given increased heat.

15 The object of my invention is to produce a safe, secure, and well-protected electric cut-out adapted principally for electroliers and other electric fixtures as a preventive of fire.

20 In the accompanying drawings similar letters of reference refer to similar parts throughout.

25 Figure 1 is a cross-sectional view of the device. Fig. 2 is a perspective view. Fig. 3 shows my device in the form of a double-pole cut-out.

30 A represents the porcelain shell surrounding the base or core B. The electric wires *w w'* are secured to the insulated porcelain base B upon a metal plate *p p'* through the medium of the screws *s s'*, which wires *w w'* are connected by a light fusible wire *f*, which will fuse or melt when the current is increased to an extent that will produce a given excess of heat, and thus the circuit will be broken and danger at the terminus avoided.

35 40 The fusible wire *f* may be connected with the wires *w w'* by any suitable means, such as by auxiliary plates *e e'*, secured to the plates *p p'* by screws *d d'*.

The porcelain shell or casing A is adapted 45 to close and protect the extremities of the electric wires *w w'* and their fusible connecting-wire *f*, secured upon the base or core B, and is preferably removably connected therewith, so that it may be removed and the 50 parts exposed when desired, it being secured to the base by a screw *t* or other suitable means. An orifice *o* is preferably provided

in the shell A over the fusible wire *f* to allow of the escape of gases or fumes when the wire *f* fuses or explodes. By thus providing this 55 orifice *o* in the outer shell or casing A the fumes and gases in escaping are thus prevented from injuring the parts of the cut-out by the force of the explosion, which injury or destruction would occur were there no vent 60 provided in the outer casing, as is the case in many cut-outs heretofore invented.

An important feature of my invention is the combination of the removable sliding shell A on the base B, removable by a turn or 65 two of the securing-screws *t*, and then simply sliding the shell off the base and exposing the parts fixed and secured as they are to the base B. In this manner a burned-out fuse may be readily renewed and a perfect connection insured before the sliding shell is replaced, which connection is in no way disturbed by the replacing of the shell.

I am aware that cut-outs having insulating-coverings are old, and these I do not claim, 75 broadly; but my invention consists in the specific construction described.

I have particularly described my device as applied to a single-pole cut-out; but it may also be constructed for a double or treble 80 pole cut-out, as desired, as shown in Fig. 3.

Having thus described my invention, what I claim, and desire to secure by Letters Patent, is—

1. In an electric cut-out, a solid base having secured thereon two ends of the electric conducting-wire, said ends connected by fusible conducting-connection, in combination with a sliding porcelain shell or casing surrounding said base and parts thereof, said shell adapted to slide on the said solid base, exposing the same and the parts connected therewith in order to allow of an examination of the parts of the cut-out and to renew a burned-out fuse and insure a perfect contact before replacing the sliding shell, in the manner and for the purpose substantially as hereinbefore set forth and described. 85 90 95

2. In an electric cut-out, a sliding porcelain covering or protector surrounding a solid base and connections of the cut-out, protecting the parts from injury and danger from contact by imperfect insulation, said sliding removable covering removable from 100

said base at will, in the manner and for the purpose substantially as hereinbefore set forth and described.

3. In an electric cut-out, a porcelain shell 5 A, inclosed solid insulating-base B, an electric fusible connection secured thereto connecting the ends of the electric wires, said shell A adapted to slide on and off said base B, and orifice provided in said shell to allow 10 of the escape of fumes and gases occasioned

by the explosion of the fusible connection *f*, substantially as hereinbefore set forth and described.

In witness whereof I have hereunto set my hand this 1st day of February, A. D. 1890.

FREDERICK G. WARRELL.
